RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

PULLING-OVER MACHINE.

1,145,380.

Specification of Letters Patent.

Patented July 6, 1915.

Application filed January 21, 1910. Serial No. 539,413.

To all whom it may concern:

Be it known that I, RONALD F. McFEELY, a citizen of the United States, residing at Beverly, in the county of Essex and State of Massachusetts, have invented certain Improvements in Pulling-Over Machines, of which the following description, in connection with the accompanying drawings, is a specification, like reference characters on the drawings indicating like parts in the several figures.

This invention relates to machines for use in the manufacture of shoes and is herein shown for the purpose of explanation as embodied in a pulling-over machine of the type of that shown in United States Letters Patent No. 1,029,387 granted on my application June 11, 1912.

One object of this invention is to provide improved operating means for tools for working on shoes and a feature of the invention consists in the combination with such a tool of operating means including a manually controlled spring for effecting initial operative movement of the tool and means to pick up the tool automatically where the spring leaves it and move it farther in the same direction while the tool maintains operative engagement with the shoe.

Other important objects of this invention are to facilitate the presentation of the shoe to the machine, to render more easy the adjustments of the upper and the last relatively and to render more effective the upper stretching operation.

Another important feature of the invention consists in provision for closing the grippers on the upper independently of the automatic operation of the machine and, preferably, one independently of another. In accordance with this feature of the invention the operator can, after positioning the work, close the grippers thereon and then inspect the shoe to ascertain if it is properly prepared for the machine's operation. Advantageously the closing mechanism is arranged so that the toe and side grippers can be closed separately. This permits the operator to position the upper first within the toe gripper with the last positioned properly lengthwise and sidewise relatively to the toe gripper and then cause the toe gripper to close upon the upper and hold it while the

upper is being positioned within the side grippers which may then be closed. In this procedure the operator is not obliged to place and maintain the upper in proper position to be seized by all the grippers before any of them can be closed. This provision is of particular value in a machine which is equipped and arranged as described in prior United States Letters Patent No. 1,030,264, granted June 18, 1910, on an application filed by me to provide gages with relation to which the last and the upper may be correctly positioned in presenting the shoe to require little or no adjustment after pulling to obtain the desired length and position of the toe tip on the last. If desired the side grippers may be closed first and the toe gripper closed later. I have shown a finger operated device for closing the toe gripper and a treadle operated device connected to the side grippers for closing them and which may be connected to the toe gripper for closing that gripper also if it has not previously been closed.

Preferably and in accordance with a further feature of the invention the grippers are, immediately after being closed, yieldingly uplifted sufficiently to straighten the upper over and about the last and, it may be, partially stretch the upper. This initial pulling of the upper has several advantages. If the upper is gripped and initially pulled at the toe first it is thereby straightened out lengthwise of the last so that the operator can see if the upper and the last are in the desired relative lateral positions and if they are not he can easily adjust them by moving the last or the toe gripper. This first pull will also straighten somewhat the sides of the upper and enter or assist in entering the sides in the side grippers. It will also render more easy the adjustment of the sides of the upper to place the tip seam ends in desired relation to their gages so that the upper will be seized and pulled with the seam approximately "straight" and the tip of a predetermined length from the seam to the end of the toe of the last. When the upper has been thus seized and straightened out without being put under heavy tension any adjustment which may be required for positioning the tip seam or any other portion of the upper by the tip

straightening mechanism or otherwise can be made without the resistance which exists from the friction of a fully tensioned upper on the last. Also adjustments made under 5 these conditions more certainly shift the upper bodily upon the last, as distinguished from increasing the tension at one point and relaxing it at another, than can be done when the upper is held under full pulling 10 strain.

Another feature of this invention is found in the provision for step by step stretching of the upper with a dwell of substantial extent between successive steps during 15 which the tension becomes distributed throughout the entire body of the upper. It is well known that if leather is pulled once and then after a dwell is further pulled the stretch taken out by the two pulls will aggregate more than could safely have been obtained by a single pull. In accordance 20 with this feature of the invention advantage is taken of this fact, with the result of obtaining a pulled-over shoe that is better fitted 25 to its last and which will require somewhat less of upper stock. Similar advantages are obtained in some degree from the arrangement by which the upper can be stretched longitudinally and transversely 30 with a substantial dwell between the stretching pulls in the two directions.

These and other features of this invention including certain details of construction and combinations of parts will be explained in connection with the following description of a preferred embodiment of the 35 invention and then pointed out in the claims.

Figure 1 is a side elevation of the machine partly in section; Fig. 2 is a plan view of 40 the gripper operating levers.

The driving mechanisms of the pulling-over machine and those other mechanisms not herein specifically described may be constructed and arranged in accordance with 45 said prior patents to which reference may be had for a full explanation of the pulling-over machine or they may be constructed and arranged in any other suitable way.

The driving mechanisms comprise a shaft 50 carrying gripper cams 2 and 4. Each cam receives a roll 5 on a slide 6. The rear slide has an upwardly extending stem 7 encircled by a spring 8 held under tension by a nut 9 against the block 10 which receives the 55 forked end of the updraw lever 12. There are two of the stems 7 and associated parts rising from the rear slide 6, one being hidden by the other in Fig. 1. These stems connect with the two side gripper levers as 60 appears in the plan view Fig. 2. The front slide 6 has a single stem 7 and associated parts connected with the rear end of the toe gripper lever 13. Each of the gripper levers is fulcrumed at 15, and the front arm 65 of each lever is formed in two sections, that

is, the main lever terminates short of the gripper attaching point, as clearly shown in Fig. 1, and the second lever, or lever arm section, 121 is pivoted on the fulcrum rod 15 and overlies the front end of the lever 12. 70 A connection is provided which normally unites the lever sections. This connection is shown as in the form of a sliding bolt 20 carried by the main section 12 and pressed forwardly by a light spring into a recess in 75 the lever section 121. A spring 22 of sufficient strength to apply a light upper stretching pull to the gripper with which it is associated is arranged under tension between the lever section 121 and the front end of 80 the other section. Each of the gripper levers for the side and toe grippers is formed alike in the respects above mentioned and the grippers are suspended from the front sections 121, 121, 131 and extend downwardly through guideways in the frame portion 124. The guideway for each side gripper is wider than the gripper carrier and the latter is formed with oppositely inclined shoulders 125 by means of which it is 85 reguided to normal position longitudinally of the shoe each time it is lowered. In this respect, as also in the construction and plan of operation of the grippers themselves, the present machine is like that shown in my 90 prior Patent No. 1,030,264 and includes the spring 170 which is under compression when the grippers are opened by the downward movement of the front arms of the gripper levers, this movement being positively effected by the rise of the slides 6 as will be 95 clearly understood.

The toe gripper lever section 131 supports a push rod 30 which extends to the seat for the latch 20 associated with the toe gripper 100 and into position where the endwise backward movement of the rod will press the latch out of its seat and allow the spring 22 to uplift the lever section 131 and the toe gripper connected therewith. In this uplifting movement the toe gripper is closed by the spring 170 and uplifted yielding by the spring 22 for seizing and straightening the upper lengthwise about the last. 110

In addition to the push rod, by means of 115 which the toe gripper may be closed and initially uplifted, there is provided a treadle 35 connected by a rod about one arm 36 of a rock shaft. The rock shaft has on its front side, lugs or fingers 38 arranged to 120 engage a shoulder on the latch 20 in each of the gripper levers. This arrangement is such, as clearly appears in Fig. 1, that depression of the treadle 35 turns the fingers 38 downwardly and backwardly in the direction to withdraw the latches 20 from their 125 seats in the front sections 121, 131 of the gripper levers and thus free the spring 22 in each gripper lever. When thus freed the springs uplift the front sections of each 130

of the gripper levers for closing and initially pulling the upper with a force determined by the tension of said springs. The portions of the latches 20 which are directly engaged by the fingers 38 are pivoted to the main portions of the latches and normally held in the path of the fingers by light springs, as shown by full and dotted lines in Figs. 1 and 2. This treadle operated mechanism above described will close all of the grippers or will close the side grippers only if the toe gripper has been previously closed by the operation of the push rod 30. If it is desirable to close the side grippers first and the toe gripper at a later time the shoulder-carrying section of the latch 20 for the toe gripper will be turned downwardly about its pivotal connection to the main portion of the latch and a suitable wedge or other device inserted in the joint at the upper side of the pivot. Whenever this wedge is withdrawn, the spring at the lower side of the pivot will force the shoulder again into position for the latch of the toe gripper lever to be operated by its finger 38. With this construction of the machine, the operator may first position the shoe with relation to the toe gripper, the inner edge of which is preferably concaved to assist in centering the toe end of the last, and then, while holding the shoe in correct relation to this gripper, may actuate the push rod 30 to trip the latch 20 for causing the toe gripper to be closed and uplifted for initially pulling the upper.

In the broadest aspect of the invention it is not essential that the toe gripper pull the upper during its initial movement before the side grippers are closed because the shoe bottom rest 126 is located in such relation to the toe gripper that the shoe can be fulcrumed on that rest to effect forward pulling of the upper in the machine preparatory to the insertion of the upper into the side grippers. Prior to this invention such preparatory forward pulling has been frequently done by the use of hand pincers just before presenting the shoe of the machine. This invention enables the machine operator to dispense with such use of hand pincers by moving the machine gripper or the last. In this movement the upper is straightened longitudinally of the last and the sides brought into condition for being conveniently positioned in the side grippers. This positioning may advantageously be effected by the two hands of the operator, one at either side of the shoe, inasmuch as the upper is held and the shoe partially supported by the toe gripper and the usual heel rest of the pulling-over machine. When an upper having a tip is being presented the operator may position the tip seam at the two sides of the shoe with relation to the front edges of the side grippers to obtain

the desired angular relation of the seam to the longitudinal axis of the last and the desired length of tip.

It should be further explained that the machine herein shown is provided with the means, including a hand lever 160 and connections to the sole rest 126 for actuating the sole rest as shown in said prior patent No. 1,029,387. This means may be employed for moving the last lengthwise within the gripped and lightly held upper for positioning the last and the upper as a whole before the final updraw.

In the foregoing statement it has been assumed that the shoe innersole has been attached to the last as is customary in the better grades of shoes and that the last may be moved by the sole rest through its connection with the innersole. If the innersole is loose on the last bottom, as in some kinds of shoes, the sole rest and its actuating mechanism may be employed for positioning the innersole lengthwise relatively to the last and the upper.

The machine is equipped with the usual tip straightening mechanism comprising the hand lever 292 and rack bars 250, 256 fully shown in said prior patents for moving the side grippers lengthwise of the last in opposite directions to effect any adjustments of the upper longitudinally around the last which may appear to be required after the upper has been pulled over the last under initial tension. The grippers can also be manipulated by the handles on the front sections of the levers 121, 131 for shifting the upper transversely of the last. These adjustments can be made while the upper is held under initial light tension by the springs 22 after the latches 20 have been tripped by the devices 30, 35.

An important advantage is gained by the provision furnished by this invention for adjusting the last and upper relatively while the upper is held under a light tension. The adjustments are thereby more easily effected, but perhaps the greater advantage is found in the fact that the upper is positioned in correct, or substantially correct, relation to the last before the main or final stretching operation so that the upper is stretched and shaped to the last in its permanent position, thus providing a better fitted shoe.

The machine is also equipped with the starting and stopping mechanism, including the treadle X⁴, of my earlier patents by which rotation of the cam shaft may be caused to pull down the slide 6 and, yielding through springs 8, pull down the rear ends of the gripper levers 12 and 13. In this movement, which is accompanied by a rise of the front ends of said levers, the latches 20 engage inclined faces 24 on the lower sides of the gripper sections 121, 131 and are forced backwardly until they reach

4
a position to enter their seats in the front gripper sections. In this rise of the front arms of levers 12 and 13, the springs 22 are again put under tension until contact is made between said arms and the sections 5 121, 131 whereupon the latter will be uplifted for further raising the grippers to effect full stretching of the upper. The machine may then come to rest automatically 10 to permit reexamination of the shoe and any further adjustment that may be required after this second step in the upper stretching operation, or this automatic stop in the machine's operation may be dispensed with and 15 the machine caused to proceed to overdraw and fasten the upper in the manner described in said prior patent.

From the foregoing description of the machine, in which its operation is also explained, it will be seen that the grippers may 20 be closed and lightly uplifted successively or simultaneously by the use of tripping devices under control of the operator, and the shoe materials and the last may then be relatively positioned and the final or full 25 stretching of the upper performed by the machine as a second step after the starting treadle X⁵⁴ has been depressed. The arrangement by which the stretching is effected in two steps with a substantial dwell between permits the upper to take the form of 30 the last under the initial tension of the first step and enables more stretch to be taken out of the upper in two steps than could 35 safely be done if the upper were pulled in a single step. It will be noted that in the power driven operation for effecting the second pulling step, the springs 22, which are instrumental in the initial operation, are put 40 under tension and secured under tension ready to be tripped in the work upon the next shoe presented to the machine.

Stops are provided on the lever sections 121, 131 to engage cushions 122 on the 45 frame of the machine to prevent danger of breakage if the tripping devices are actuated when no shoe is in the machine. When they are so actuated the springs 22 are liable to throw the lever sections upwardly with considerable force.

Having explained the nature of this invention, and described a preferred construction embodying the same, I claim as new and desire to secure by Letters Patent of the 55 United States:—

1. A pulling-over machine, having in combination, grippers for engaging an upper at the toe and at opposite sides of a shoe, manually controlled means by which said grippers may be closed successively and actuated for initially pulling the upper, and power driven means for further actuating said grippers in the same direction.

2. A pulling-over machine, having in combination, grippers for engaging an upper

at the toe and at opposite sides of a shoe, manually controlled means for closing the toe gripper and a separate means for closing the opposite side grippers prior to the power actuation of the gripper, and power driven means for actuating the grippers to pull the upper perpendicularly to the last bottom simultaneously with one another.

3. A pulling-over machine, having in combination, grippers for engaging an upper 75 at the toe and at opposite sides of a shoe, manually controlled means connected with all the grippers to cause closing, and separate means to be used optionally for closing the toe gripper alone.

4. A pulling-over machine, having in combination, grippers for engaging an upper at the toe and at opposite sides of a shoe, and operating mechanism therefor, including power driven means arranged to permit at 25 a predetermined point in machine's operation a dwell of substantially indefinite duration between two portions of the updrawing pull of all the grippers.

5. A pulling-over machine, having in combination, grippers for engaging an upper at the toe and at opposite sides of a shoe, and operating mechanism including means for actuating all the grippers for initially pulling the upper and additional means to be 95 started at the will of the workman for further actuating the grippers in the same direction for finally pulling the upper.

6. A pulling-over machine, having in combination, grippers for engaging an upper 100 at the toe and at opposite sides of a shoe, manually controlled means for effecting closing of the grippers and for releasing special springs which actuate the grippers to straighten out the upper, and power 105 driven means for actuating the grippers for completing the operation of updrawing the upper.

7. A pulling-over machine, having in combination, grippers for engaging an upper 110 at the toe and at opposite sides of a shoe, manually controlled means adapted for separately closing the toe and side grippers and releasing special springs by which each gripper is initially moved to straighten the upper seized by it, and additional means by which the grippers may be actuated for further pulling the upper in the same direction.

8. A pulling-over machine, having in combination, grippers for engaging an upper at the toe and at opposite sides of a shoe, to which the shoe is presented in the hands of the workman, hand controlled means for closing the toe gripper and causing it to straighten the upper lengthwise of the shoe, means capable of operation thereafter to close the side grippers while the upper is held in proper relation thereto in the two hands of the operator, and power driven 125 means for thereafter actuating all the grippers.

pers substantially perpendicularly to the last bottom to pull the upper.

9. A pulling-over machine, having in combination, grippers for engaging an upper at the toe and at opposite sides of a shoe, and operating mechanism therefor arranged to insure the updrawing movement of the grippers being effected in two distinct steps with an interval of substantial duration between them.

10. A pulling-over machine, having in combination, grippers for engaging an upper at the toe and at opposite sides of a shoe, and operating mechanism therefor arranged to permit a successive initial pulling by the toe and side grippers and a final pulling by a movement of all the grippers simultaneously.

11. A pulling-over machine, having in combination, grippers for engaging an upper at the toe and at opposite sides of a shoe, a shoe bottom rest relatively to which the toe gripper has an upper receiving position below the rest to permit the operator to position the toe end of the last against the toe gripper as a gage and with the upper in said toe gripper, actuating mechanism permitting the operator then to close the toe gripper and thereafter to position the upper within and the tip seam relatively to the side grippers and close the side grippers, and power driven mechanism for subsequently actuating the grippers to pull the upper.

12. A pulling-over machine, having in combination, grippers for engaging an upper at the toe and at opposite sides of a shoe, and operating mechanism therefor arranged to hold the upper under a light tension by all three grippers while relative positioning adjustments of the last and the upper are made, said mechanism including additional devices for effecting further pulling of the grippers in the same direction upon the adjusted upper.

13. A pulling-over machine, having in combination, grippers for engaging an upper at the toe and at opposite sides of a shoe, and operating mechanism therefor arranged to effect step by step updrawing of the upper by said toe and side grippers with opportunity for adjustment of the upper upon the last between steps, said mechanism including power driven devices for effecting the final updrawing of the adjusted upper by the grippers.

14. A pulling-over machine, having in combination, grippers for engaging an upper at the toe and at opposite sides of a shoe, operating mechanism for causing the grippers to seize and straighten the upper, means for moving the grippers to adjust the upper, additional mechanism for further actuating the grippers to pull the upper in its adjusted

position, and means for reguiding the grippers to starting position.

15. A pulling-over machine, having in combination, grippers, means whereby the grippers may be actuated for seizing and lightly pulling the upper and then come to rest, means whereby the grippers and the last may be adjusted relatively to position the upper while it is held under light tension, and power driven means for subsequently effecting further updrawing movement of the grippers for finally tensioning the upper over the last in its correctly adjusted position.

16. A pulling-over machine, having in combination, grippers for engaging and pulling an upper over a last, a rest for the sole of the last, operating mechanism for the grippers including means for closing the grippers and putting the upper under initial tension, additional means for further pulling the upper, and means for actuating the sole rest for effecting relative longitudinal adjustment of the last and the shoe stock while the upper is held under the initial tension.

17. A pulling-over machine, having in combination, a gripper lever and actuating mechanism therefor, said lever being formed in relatively movable sections, one of which is connected to said actuating mechanism and the other to the grippers, a spring interposed between the two sections, a latch holding the two sections in normal relation with the spring under tension, and a tripping device for releasing the latch to permit the spring to effect movement of the gripper independently of said actuating mechanism.

18. A machine of the class described, having in combination with suitable actuating mechanism and a gripper, a two-part gripper lever, a normally tensioned spring, and means under control of the operator for causing said spring to move one lever part relatively to the other for initially pulling the upper independently of said actuating mechanism.

19. A pulling-over machine, having in combination, last engaging means, a gripper, mechanism for actuating the gripper, and a spring normally put under tension by said mechanism and arranged to be tripped by the operator to close the gripper independently of said actuating mechanism.

20. A machine of the class described having, in combination, a gripper, a spring constructed and arranged to lift the gripper for pulling the upper preliminarily, and means to pick up the gripper at the point to which the spring lifted it and further move the gripper to effect additional pulling of the upper.

21. A machine for use in the manufacture of shoes having, in combination, a tool for

- operating on a shoe, and actuating means for moving the tool to perform its intended operation; including a manually controlled spring for effecting initial operative movement of the tool, and automatic means to pick up and move the tool farther in the same direction while it maintains operative engagement with the shoe from the point where the spring left it.
- 10 22. A pulling-over machine having, in combination, means for initially pulling an upper having provision for permitting adjustment of the pulled upper while it is lightly held and power-actuated means for further stretching the upper by an updrawing movement.
- 15 23. A pulling-over machine, having in combination, grippers for engaging an upper at the toe and at opposite sides of the shoe, means for effecting closing of the toe grippers, separate means for manually controlling the closing of the side grippers, and power operated means for actuating all the grippers to pull the upper.
- 20 24. A pulling-over machine, having in combination, grippers for engaging an upper at the toe and at opposite sides of the shoe, manually controlled means for effecting closing of the toe grippers, independent manually controlled means for effecting the closing of the opposite side grippers simultaneously, and power operated means for actuating all the grippers to pull the upper.
- 25 25. A pulling-over machine, having in combination, grippers for engaging an upper at the toe and at opposite sides of the shoe, hand controlled means for effecting the closing of the toe grippers, means arranged to be operated by the foot for controlling the closing of the side grippers simultaneously with one another, and power operated means for actuating all the grippers to pull the upper.
- 30 26. A pulling-over machine, having in combination, grippers for engaging an upper at the opposite sides of the shoe, means for actuating the grippers to effect a straightening tension upon the upper and permit adjustment thereof relatively to the last, and a means connected with opposed side grippers for effecting a final pull upon the adjusted upper in the same direction as the upper straightening movement of the grippers.
- 35 27. A pulling-over machine, having in combination, grippers for engaging an upper at the opposite sides of a shoe, springs arranged to be released for raising the grippers to produce a straightening tension upon the upper, means for moving the side grippers to adjust the upper longitudinally of and around the last, power actuated means for further actuating the grippers for effecting a further pull upon the adjusted upper, and means for reguiding the grippers to normal position after the pulling operations.
- 40 28. A pulling-over machine having, in combination, grippers for engaging an upper at the toe and at opposite sides of the shoe, manually controlled means for effecting closing of the side grippers, and power operated mechanism which will close the side grippers if the manually controlled means is not used, said mechanism being constructed and arranged to lift said grippers to pull the upper that has been seized by the grippers.
- 45 29. A pulling-over machine having, in combination, a shoe bottom rest, side grippers, a toe gripper, power operating means for moving said grippers to pull the upper, a spring through which closing of the toe gripper may be effected, means for maintaining the spring under stress, and means by which said spring can be released and caused to close the toe gripper, said bottom rest being located relatively to the toe gripper to allow the last to be fulcrumed thereon for effecting pulling of the upper between the last and the toe gripper prior to starting the power mechanism for causing the side grippers to pull.
- 50 30. A pulling-over machine having, in combination, a shoe bottom rest, a toe gripper, power operating means for moving said gripper to pull the upper into position to be fastened, a spring through which closing of the gripper may be effected, means for maintaining the spring under stress, and means by which said spring can be released and caused to close the gripper, said bottom rest being located relatively to the gripper to allow the last to be fulcrumed thereon for effecting pulling of the upper between the last and the gripper prior to starting the power mechanism.
- 55 31. In testimony whereof I have signed my name to this specification in the presence of two subscribing witnesses.
- RONALD F. McFEELY.
- Witnesses:
- LEONARD M. JOHNSON,
CHARLES H. HOYT.

Corrections in Letters Patent No 1,145,380.

It is hereby certified that in Letters Patent No. 1,145,380, granted July 6, 1915, upon the application of Ronald F. McFeely, of Beverly, Massachusetts, for an improvement in "Pulling-Over Machines," errors appear in the printed specification requiring correction as follows: Page 3, line 48, for the word "of" read *to*; page 4, line 70, claim 2, for the word "gripper" read *grippers*; and that the said Letters Patent should be read with these corrections therein that the same may conform to the record of the case in the Patent Office.

Signed and sealed this 22d day of February, A. D., 1916.

[SEAL.]

Cl. 12-4.

R. F. WHITEHEAD,
Acting Commissioner of Patents.
